UNITED STATES PATENT OFFICE.

WILLIAM F. BUCK, OF CHICAGO, ILLINOIS.

WATER-LEVEL-DEMONSTRATING DEVICE.

1,087,350.

Specification of Letters Patent.

Patented Feb. 17, 1914.

Application filed August 30, 1911. Serial No. 646,875.

To all whom it may concern:

Be it known that I, WILLIAM F. BUCK, a citizen of the United States, and resident of Chicago, in the county of Cook and State of Illinois, have invented a certain new and useful Improvement in Water-Level-Demonstrating Devices, of which the following is a description, reference being had to the accompanying drawings, which form a part 10 of my specification.

My invention relates more especially to a device whereby the effect of track gradient upon the level of the water in the boiler of a locomotive may be graphically demonstrated; the device being so arranged that the per cent. of grade will be indicated and the effect or level of any given gage of water in the boiler demonstrated, as will more clearly be understood from the following 20 detailed description.

In the drawings: Figure 1 illustrates my improved device in front elevation, demonstrating the effect on a given gage of water in the boiler, when a locomotive is on a 25 level; a portion of the supporting frame being broken away. Fig. 2 is a similar view of same, illustrating the effect on the given gage of water in the boiler when a locomotive is descending a grade of approximately three per cent.; the lower portion of the supporting frame being broken away. Fig. 3 is a horizontal sectional view taken on the line 3—3 of Fig. 1. Fig. 4 is a detail view of the main or central pivotal 30 point, taken on line 4—4 of Fig. 1, looking down. Fig. 5 is a detail view, in section, of a tension device employed in connection with the water level indicating mechanism.

Fig. 6 is a front elevation of a modified construction. Fig. 7 is a top plan view of same. Fig. 8 is a side elevation of same, with the lower part of the supporting frame broken away. Fig. 9 is a detail sectional view taken on the line 9—9 of Fig. 6.

As an exemplification of my invention, I show the device provided with standards or supporting frame 10, of any suitable construction, having the uniting members 11 and 12, and vertically extending member 13. The frame is designed to stand upon the floor, and is made of a suitable height to adapt it to the uses for which the device is intended. A display board or member 14 is pivotally secured at its center of gravity 50 to frame-member 13, by the pintle 15, which

is secured to the member 14 in any suitable manner; for example, the pintle 15 is shown provided with a flange portion whereby it may be secured to member 14, while the outer end thereof is shown screw-threaded 60 to receive a nut or washer as shown in Fig. 4; the pintle 15 is preferably passed through a ferrule or bushing 15', secured within the opening in frame-member 13. Member 14 is intended to be provided with a longitudinal 65 sectional view of a locomotive boiler; this may either be drawn or painted on member 14, or the drawing may be on a separate board or light frame, and secured to member 14.

Pivotedly mounted on the plate or upwardly extending lug 16 is a lever 17, which extends adjacent the upwardly extending slotted member 18, secured on cross-member 12 of the frame; and the lever 70 75 17 may be clamped or held in the desired position by the butterfly-nut 19. One end of lever 17 is pivotally secured to link 20, which link is in turn pivoted to carrier-member or board 14, at a point intermediate 80 of the pivotal point 15 and one end of the member 14. The other or free end of lever 17 is made pointed, so as to act as an indicator in connection with the scale 21, of suitable description, whereby the per cent. of 85 incline or decline of the link-end of carrier-member 14 may be indicated. The scale 21 is rigidly secured to upper cross-member 12.

It is evident from the construction shown and described that the adjusted position of 90 member 14 can be maintained by tightening the clamp 19 and holding lever 17 against the quadrant 18.

Pivotedly secured to the frame-member 12, by hangers 22, are a pair of levers 23 and 24, whose inner or adjacent ends are united by link 25. The outer ends of levers 23 and 24 are provided with the studs or pins 26, which may be screwed into or otherwise secured to the levers 23 and 24. The 95 pin-carrying or outer ends of levers 23 and 24 are arranged in the same horizontal plane, so that a cord or wire 27, which reaches from pin to pin across the face of carrier-member 14 and the drawing secured thereon, will extend in the same horizontal plane throughout its length.

In order that the wire or cord 27 may be held taut, in any adjusted position of the levers, I provide a spring tension device 28. 100 105 110

One end of wire or cord 27 is secured to the end of plunger 29, which is controlled by the coiled spring 30,—see Fig. 5,—while a short wire or cord may be passed through the eye 31, and also be secured to the pin 26 at that end of lever 24, as can more clearly be seen in Fig. 3.

To maintain the levers 23 and 24 in their adjusted positions, and also to permit of their easy operation, I extend the end of one of the levers, for example lever 24, so as to form a handle, which is provided with a latch or spring-clamp 32, which engages with the slotted member 33, secured to the frame, as clearly shown in Fig. 1.

It is evident from the construction, that when the latch 32 is released from engagement with member 33, and lever 24 is swung about its pivotal point, lever 23 will be moved 10 in a similar manner by reason of the link connection 25 between the levers, thereby bringing the outer ends of both levers into the same adjusted horizontal plane. When the ends of the levers are swung out of the 20 horizontal plane occupied by their respective pivotal points on hangers 22, it is evident that the distance between pins 26, 26, will be altered or shortened; the cord or wire 27 will however be kept taut by the action of spring 30 on the plunger 29 of the 30 tension device 28.

The object of the invention is to instruct engineers and others as to the effect on the water level in the boiler when the locomotive ascends or descends the various grades 35 encountered by them on their respective runs; the mechanism being readily adjustable so as to demonstrate the effect with varying gages of water.

40 The carrier member or board 14 is provided with a scale drawing or diagrammatic view of a locomotive boiler as represented in the drawings; the drawing being placed on member 14 in any of the ways hereinbefore described. When it is desired to employ the device, the boiler, or drawing thereof, is adjusted to a level position, which may be accomplished by swinging board or member 14 by hand until the indicator or end of lever 17 points to zero on the scale 21,—which indicates the grades,—as shown in Fig. 1. The board or member 14 may be held in the desired position by the clamping or butterfly nut 19. Having adjusted the 45 boiler-drawing, adjust the position of cord or wire 27 to the gage or water level desired for the purpose of demonstration, by grasping the end of lever 24 and latch 32, thereby moving the pins 26 into the horizontal plane 50 of the water level desired. After the water-level indicating cord or wire has been adjusted, clamping nut 19 is then unscrewed so that board or carrier-member 14 may be 55 swung to indicate a locomotive either ascending or descending a grade, lever 17

showing on scale 21, the percentage of grade being ascended or descended. The water level cord or wire 27, which extends across the face of the scale drawing, will indicate the level of water from back boiler head to the front flue sheet. It is thus apparent that the depth of water over the crown sheet and the changes due to the various grades may be clearly observed by the use of my improved device, as illustrated in Fig. 2, 70 75 wherein the device is adjusted to demonstrate the level of the water when a locomotive is descending a three per cent. grade as shown by the scale.

The device may be altered in a number of details, as for example, in Figs. 6, 7, 8, and 9, I show a modified construction wherein the water level indicating means consists of a straight edge 34. When this construction is employed, levers 23 and 24, latch 32, and tension device 28 may be dispensed with. The frame or uprights are each provided with the guides 35, 35, whose construction is clearly shown in Figs. 6 and 8. A thumb nut 36 is screwed onto a pin 37, which extends through a slot in the guides 35 and a hole in each end of the straight edge 34, so that the pin 37 may slide up and down in the slot of the guides 35, while the screwing up of nuts 36 will firmly clamp or hold the straight edge in its adjusted position, and the upper edge of member 34 will represent the surface of the water in the boiler. The operation of this construction is of course similar to that of the construction shown in the previous figures.

I have briefly stated the purpose of my invention, and have shown and described what I believe to be the simplest and best constructions, but the constructions may be altered in certain details without departing from the spirit of my invention, and I do not wish to be understood therefore as limiting myself to the exact constructions shown and described; but

What I claim as my invention and wish to secure by Letters Patent is:—

1. A device of the class described, comprising a diagram-carrying member, means for supporting said member and adapted to give angular movement thereto in a vertical plane, and means extending longitudinally of said member and adapted to be adjusted vertically but be maintained in a horizontal plane whereby different levels in a horizontal plane on said member may be indicated.

2. A device of the class described comprising a diagram-carrying member oscillatingly mounted so as to be given angular movement in a vertical plane to indicate track gradient, and means arranged to extend across the face of said member and adapted to be adjusted vertically, said means extending in the same horizontal plane

throughout, so that different horizontal levels may be indicated on said diagram-carrying member.

3. A device of the class described, comprising a diagram-carrying member oscillatingly mounted so as to swing vertically, means arranged to be affected by the movement of said member to indicate the degree of vertical angular movement given said member, and mechanism, adjustable vertically, arranged to extend in a horizontal plane across the face of said member whereby different levels in a horizontal plane on said member may be indicated.

15 4. A device of the class described, comprising a pivotally mounted member arranged to swing vertically, means connected with said member arranged to indicate the degree of angular movement of said member and hold the latter in its adjusted position, and vertically adjustable mechanism arranged to maintain a level line across the face of said member.

25 5. A device of the class described comprising a carrying-member arranged to be given angular movement in a vertical plane, means arranged to be affected by said member to indicate the degree of vertical angular movement of said member, a pair of levers arranged to move in unison and adapted to carry a cord or wire and maintain a level line across the face of said member.

30 6. A device of the class described comprising a carrying-member pivotally mounted so as to be adjusted in a vertical plane, a scale graduated in per cent. grade, a lever adapted to be affected by said member and arranged to indicate on the scale the vertical angular adjustment of said member, and means for maintaining a level line across

the face of said member, whereby different levels in a horizontal plane on said member may be indicated.

7. A device of the class described, comprising a carrying-member pivotally mounted so as to permit of angular adjustment in a vertical plane, means arranged to be affected by said member to indicate the degree of angular vertical adjustment thereof, and a pair of vertically adjustable levers arranged to move in unison and hold a cord or wire in a level line across the face of said member.

15 8. A device of the class described comprising a carrying-member pivotally mounted substantially at its center of gravity so as to permit of angular adjustment in a vertical plane, means arranged to be affected by said member to indicate the degree of vertical angular adjustment of the member, a pair of vertically adjustable levers arranged to move in unison and hold a cord or wire in a level line across the face of said member, and means for maintaining the cord or wire taut during the vertical movement of said levers.

25 9. A device of the class described, comprising a carrying-member mounted near its center of gravity so as to permit of angular adjustment in a vertical plane, means arranged to be affected by said member to indicate the degree of vertical angular adjustment, means arranged to maintain a vertically adjustable level line across the face of said member, and mechanism for holding said means in place.
